DOOR KNOCKER

William F. Hitchcock, Danvers, Mass.

Application November 27, 1950, Serial No. 13,140

Term of patent 14 years

(Cl. D10—7)

To all whom it may concern:

Be it known that I, William F. Hitchcock, a citizen of the United States, residing at Danvers, in the county of Essex and State of Massachusetts, have invented a new, original, and ornamental Design for Door Knockers, of which the following is a specification, reference being had to the accompanying drawing, forming part thereof.

Figure 1 is a front elevational view of a door knocker, showing my new design.

Figure 2 is a side elevational view thereof.

Figure 3 is a rear elevational view thereof.

Figure 4 is a top plan view thereof.

The broken line wording of Figure 1 of the drawing is for illustrative purposes only.

I claim:

The ornamental design for a door knocker, as shown and described.

WILLIAM F. HITCHCOCK.
